UNITED STATES PATENT OFFICE.

ARTURO FONTS, OF NEW YORK, N. Y.

COMB.

SPECIFICATION forming part of Letters Patent No. 762,037, dated June 7, 1904.

Application filed November 11, 1903. Serial No. 180,704. (No model.)

To all whom it may concern:

Be it known that I, ARTURO FONTS, a citizen of the Republic of Cuba, and a resident of the city of New York, borough of Manhattan, in 5 the county and State of New York, have invented a new and Improved Comb, of which the following is a full, clear, and exact description.

This invention relates to certain novel and 10 useful improvements in combs, and appertains particularly to ladies' hair-combs, and has an improved attachment for retaining the same securely in position.

One of the disadvantages incident to the 15 hair-combs now in use is that owing to their peculiar formation when placed in position in the hair the comb is liable to become loosened, thereby loosening the hair, and oftentimes the comb falls or drops entirely from the head and 20 is either broken or lost.

I have therefore particularly in view as an 25 object the provision of a device designed to be secured to the comb, whereby the comb will be clasped or held firmly in the hair, obviating entirely the possibility of the comb becoming loose and falling from the hair.

A further object of my invention is to provide a comb which will embody the essential and desired features of convenience, neatness, 30 and simplicity.

With these objects and others of a similar nature in view my invention consists in the construction, combination, and operation of parts, as is described in this specification, illustrated in the accompanying drawings, and set forth in the annexed claims.

Reference is to be had to the accompanying drawings, forming a part of this specification, in which similar characters of reference indicate corresponding parts in all the figures.

Figure 1 is a view in elevation of a comb embodying my invention. Fig. 2 is a sectional view of my improved comb, showing the same in use, said view being taken approximately on the line 2 2 of Fig. 1. Fig. 3 is an enlarged view showing a tooth of the comb and a tooth of the clamping-plate contacting with the comb-tooth, and Fig. 4 is a

transverse sectional view taken through a tooth of the comb and the adjacent contacting 50 concaved tooth of the clamping-plate.

Referring now to the accompanying drawings, *a* designates a hair-comb of any ordinary and well-known shape, said comb comprising a top edge portion 5, which is slightly 55 curved or bowed, and a plurality of relatively long teeth 6, which are also concaved or curved below the general plane of curvature of the top edge portion of the comb.

In order to secure the comb within the hair, 60 I fasten to the inner face of the top portion 5 thereof, through the medium of rivets or otherwise, a plate 7, which may be formed of metal or any suitable material, said plate being approximately of a width equal to the 65 width of the top body portion of the comb and provided near the center of each of the side edges with a lug 8, there being, of course, two of such lugs. Extending between the lugs and supported thereby is a pivot-bar 9, carrying the top or clamping plate 10 of the device, 70 said clamping-plate being of any suitable shape and material, and being approximately equal to the width of the plate 7 and, generally speaking, of the same size. Said plate has 75 depending therefrom a plurality of concaved or grooved teeth 11, which teeth are each bent in toward the comb and extend approximately parallel to and normally in contact with the teeth 6 of the comb to a point about midway 80 the length of such teeth, although it is to be understood that the teeth of the clamping-plate may be made longer or shorter, as desired. In order to keep the teeth of the clamping-plate normally in a closed position, or in 85 contact with the teeth of the comb, I provide a tension-spring 12, coiled about the pivot-bar 9, which spring has a tendency to hold the toothed portion of the clamping-plate against the teeth of the comb.

From the above description, taken in connection with the accompanying drawings, the manner of employing my improved comb will be readily apparent. The upper portion of the clamping-plate is pressed so as to draw the 95 teeth of such plate away from the comb and

the comb is then thrust into the hair, as is clearly shown in Fig. 2. The clamping-plate is then released, and the teeth thereof, being curved and grooved or concaved, act in conjunction with the comb to securely retain the latter in the hair and prevent the accidental disengagement or removal of the comb.

Having thus described my invention, I claim as new and desire to secure by Letters Patent—

10 1. The combination of a comb, a plate rigidly secured thereto, lugs extending from said plate, and a toothed clamping-plate pivotally supported from the lugs and designed to act in conjunction with the teeth of the comb for retaining the comb in the hair, each tooth of

the plate being grooved to receive an adjacent tooth of the comb.

2. The combination of a comb, and a toothed clamping-plate pivotally secured to said comb, each tooth of the plate being grooved longitudinally to receive an adjacent tooth of the comb.

In testimony whereof I have signed my name to this specification in the presence of two subscribing witnesses.

ARTURO FONTS.
